US00D889505S

(12) **United States Design Patent** (10) Patent No.: **US D889,505 S**
McLean et al. (45) Date of Patent: ** Jul. 7, 2020

(54) **DISPLAY SCREEN WITH GRAPHICAL USER INTERFACE FOR MONITORING REMOTE VIDEO CAMERA**

(71) Applicant: **GOOGLE LLC**, Mountain View, CA (US)

(72) Inventors: **Melissa McLean**, Novato, CA (US); **Michael Mizono**, Mountain View, CA (US); **Lauren Von Dehsen**, San Francisco, CA (US); **Joe Delone Venters**, Alameda, CA (US); **Tracy Kuwatani**, Mountain View, CA (US); **Zachery Kennedy**, San Jose, CA (US)

(73) Assignee: **Google LLC**, Mountain View, CA (US)

(**) Term: **15 Years**

(21) Appl. No.: **29/635,071**

(22) Filed: **Jan. 26, 2018**

CLAIM

An ornamental design for a display screen with graphical user interface for monitoring remote video camera, as shown and described.

DESCRIPTION

This application is related to the following applications, all of which are hereby incorporated by reference in their entirety:

U.S. patent application Ser. No. 29/530,440, titled “User Interface for Mobile Camera History Having Event-Specific Activity Notifications,” filed Jun. 16, 2015;

U.S. patent application Ser. No. 29/530,441, titled “Display Screen with Graphical User Interface for Mobile Camera History Having Collapsible Video Events,” filed Jun. 16, 2015;

U.S. patent application Ser. No. 14/738,928, titled “Methods and Systems for Smart Home Automation Using a Multi-function Status and Entry Point Icon,” filed Jun. 14, 2015; U.S. patent application Ser. No. 14/739,412, titled “Methods and Systems for Presenting Alert Event Indicators,” filed Jun. 15, 2015; and

U.S. patent application Ser. No. 14/739,427, titled “Methods and Systems for Presenting a Camera History,” filed Jun. 15, 2015.

FIG. 1 is a front view of a graphical user interface for a display screen of an electronic device or portion thereof showing our new design; and,

FIG. 2 is an enlarged portion of FIG. 1 thereof.

The gray shading represents a contrast in appearance.

The dot-dash lines in FIGS. 1 and 2 illustrate the perimeter of a portion of the display screen that is shown enlarged in FIG. 2 and form no part of the claimed design. The remaining broken lines showing a portion of a display screen of a graphical user interface, text, and other elements in the FIGS. 1 and 2 are included for showing portions of the article and form no part of the claimed design.
